UNITED STATES PATENT OFFICE.

SAMUEL SHULL, OF PHILADELPHIA, PENNSYLVANIA.

RAIL JOINT.

Application filed June 12, 1922. Serial No. 567,565.

To all whom it may concern:

Be it known that I, SAMUEL SHULL, a citizen of Russia, residing at Philadelphia, in the county of Philadelphia and State of Pennsylvania, have invented certain new and useful Improvements in Rail Joints, of which the following is a specification.

My invention relates to rail joints and the object thereof is to provide an improved joint construction for connecting the adjacent ends of rail sections so as to present a substantially continuous rail; to provide for displacement of the ends caused by expansion and contraction; to obviate the use of fish plates and bolts or other similar fastenings; thereby reducing the possibility of tampering with the joints, and to facilitate the connection and disconnection of the rail sections.

These objects, and other advantageous ends which will be described hereinafter, I attain in the following manner, reference being had to the accompanying drawings in which—

Figure 1 is a disassembled side elevation showing the adjacent ends of two rail sections equipped with the improved joint,

Figure 2 is a similar view with the parts assembled,

Figure 3 is a central horizontal sectional plan through the web of the joint,

Figure 4 is a fragmentary vertical sectional view taken on the line 4—4 of Figure 3 with the intermediate portion in elevation,

Figure 5 is a perspective view of a connecting part employed in connection with the joint,

Figure 6 is an end view of the part shown in Figure 5,

Figure 7 is a bottom view of one end of the connecting part shown in Figures 5 and 6,

Figure 8 is a plan view of one end of a rail section, and

Figure 9 is an end view of the part shown in Figure 8.

Referring to the drawings, the rail ends are designated at 12 and 13 and each is provided with an extended thickened web portion 14 produced by cutting off the ball or tread portion 15 to the web so that the web 14 and the base 16 project from the end of the ball portion. The web 14 has vertical lateral extensions or ribs 17 and the end is undercut or beveled as indicated at 18. The opposite flanges of the base 16 are recessed at each side of the web as indicated at 19 so

that a connecting part 20 which connects the rail ends, may rest therein. Connecting part 20 has extensions 21 provided with sockets 22 to receive the web portions of the rail ends. The sockets have walls 23 inclined at an angle in the same general direction as the undercut or beveled ends 18 of the web portions 14.

The opposite sides of the extensions 21 at the inner faces thereof are provided with vertical notches 24 communicating with the bottom edges of the sides of the extensions 21 which are open at the bottom, by reason of the ends of the base flange 25 being cut away, except that the base flanges project beyond the intermediate recesses or notches 26 to provide openings in the bottom of the joint for a purpose to be hereinafter more fully set forth. The lateral extensions or ribs 17 may be of convex or other cross section and the notches 24 are beveled toward the end walls 23 so as to allow slight longitudinal displacement to compensate for contraction and expansion.

Wedges 27 are fitted between the inclined portions 18 and 23 when connecting member 20 is dropped into position with the ribs 17 engaging the notches 24, so that end-wise separation or disconnection of the rail sections 12 and 13 from connecting member 20 and with respect to each other, is prevented. The rail sections and connecting member are secured to the ties in the usual or any preferred way, before, or after the connecting member is dropped into position as described, when the sockets 22 receive the extended web portions 14, the wedges 27 are confined in the sockets against the inclined walls 23 by inserting pins 28 in openings 29 in the sides of the extensions 21. Upon removing the pins, the wedges will drop or wedge between the adjacent beveled ends 18 and 23 and prevent displacement or lifting out of the connecting member, so that the liability of the joint being tampered with is reduced to a minimum and the use of fish plates, bolts or other fastenings which are likely to get loose, is obviated.

The pins 28 may be inserted to hold the wedges beneath the ends 18 and against the walls 23, instead of in the position shown in Figure 4 when serving to free the ends of the rail sections from the connecting member, so that the connecting member may be lifted out of position together with the wedges, when it is desired to effect the dis-

connection of the rail sections for replacement, repair or otherwise. In addition, the notches 26 provide means for the insertion of an instrument at the bottom when the 5 ends 18 and 23 oppose each other, in order that the wedges may be placed into the cut-out portions or sockets 22 and against the end walls 23, in order that the connecting member may be removed and also that the 10 wedges will not drop out of position when the parts are being assembled or disassembled. This construction is used in lieu of or in conjunction with the pins 28.

While I have described my invention as 15 taking a particular form, it will be understood that the various parts of my invention may be changed without departing from the spirit thereof, and hence I do not limit myself to the precise construction set 20 forth, but consider that I am at liberty to make such changes and alterations as fairly come within the scope of the appended claims.

Having thus described my invention, what 25 I claim as new and desire to secure by Letters Patent is:—

1. A rail joint comprising ends of rail sections having projecting portions; a connecting member between the projecting portions having sockets to receive the same; means in the sockets to limit longitudinal movement of the projections, and means in the sockets for preventing vertical movement of the connecting member.

35 2. A rail joint comprising ends of rail sections having projecting portions; a connecting member having sockets to receive the projecting portions; means in the sockets to limit longitudinal movement of the 40 projecting portions, and wedges in the sockets for preventing vertical movement of the connecting member.

3. In a rail joint, the combination with two rail ends having the ball portions there- 45 of cut away to the web and the ends of the web undercut; of a connecting part having extended web and ball portions forming sockets at the ends, the sockets being open at the bottom and having end walls inclined 50 in the same general direction as the ends of the rails, the side faces of the rail webs and socket walls having co-acting portions

to lock the parts against longitudinal separation, and means between the beveled ends to prevent vertical displacement of one part with respect to the other.

4. In a rail joint, the combination with two rail ends having the ball portions there- 55 of cut away to the web and the ends of the web undercut; of a connecting part having 60 extended web and ball portions forming sockets at the ends, the sockets being open at the bottom and having end walls inclined in the same general direction as the ends of the rails, the side faces of the rail webs and 65 socket walls having co-acting portions to lock the parts against longitudinal separation, and wedges movably positioned between the beveled ends to hold the connecting part against vertical displacement and 70 adapted to be shifted beneath the undercut ends to permit vertical displacement of the connecting part.

5. In a rail joint, the combination with 75 ends of adjacent rails having extended web and base flanges, said web portions having vertical side projections and having the ends thereof beveled and the flanges having longitudinal recesses; of a connecting part 80 having extended web and ball portions, said web portions being off-set laterally to receive the ends of the rail sections in the cut-out portions thus formed, the ends of the connecting part being beveled in the same direction as the ends of the rail sections, said web portions having vertical notches 85 receiving the projections and permitting vertical displacement of the connecting part but preventing longitudinal disconnection of the rail sections with respect thereto; wedges disposed between the beveled ends with their enlarged portions upward to resist vertical displacement of the parts, and 90 means for disposing the wedges in such position as to permit said vertical displacement.

In testimony whereof I have signed my name to this specification in the presence of two subscribing witnesses.

SAMUEL SHULL.
